SKEWBACK STRUCTURAL SHAPE FOR
FURNACE STRUCTURES

Edward W. Pottmeyer, Pittsburgh, Pa., assignor,
by mesne assignments, to Blaw-Knox Company,
Pittsburgh, Pa., a corporation of Delaware

Application October 19, 1950, Serial No. 190,979

4 Claims. (Cl. 122—497)

1

This invention relates to an elongated skewback structural shape preferably made of ferrous metal for use in oven-hearth furnaces or the like. More particularly, it relates to such a structural shape in the general form of a skewback member having a markedly increased section modulus about its vertical neutral axis, while at the same time providing cooling passages for the flanges thereof. In addition, the new skewback structural shape of this invention is 10 reversible whereby the life thereof may be markedly extended.

In furnace structures such as an open-hearth furnace, the framework thereof is made of steel. In order to protect such framework from exposure to the high temperatures inside the furnace, in those furnace structures in which the refractory roof is arched from front to back but not from side to side, structural steel skewback channels are employed as an element of the framework across the back and front of the furnace to support the weight and thrust of the arched roof. Such skewback channels, due to deterioration of the protective refractory of the roof, may expose a certain portion of the metal thereof to the flame and temperatures inside the furnace. It is necessary in most industrial furnaces to replace such doorframes and to either replace or reline the doors with refractory during the life of the furnace. This can generally 20 be conveniently accomplished at any time. But because of the foundation nature of the skewback channels, the replacement thereof can be undertaken only after a portion of the roof of the furnace has been torn down for rebuilding. Such rebuilding may occur two or more times 30 during a furnace campaign.

In such furnace structures the skewback channel across the framework at the front of the furnace may be bolted to the adjacent vertical buckstays; or alternatively, the skewback channel may be suspended on rods hanging from the furnace framework binding and bear against the buckstays without any rigid connection thereto. The conventional skewback channel is protected 40 against the heat of the furnace by a skewback brick and the top of the refractory arch constructed across the top of the charging openings. In those furnaces employing an archless type of doorframe, a water-cooled ledge may be provided in the doorframe which extends under the lower flange of this conventional skewback channel to keep it from burning away in the course of operation. In almost all of such cases, the tops 50 of the doorframe used in such furnace structures

2

rest against or are connected to the skewback channel when in position around its respective furnace opening. These doorframes are readily removable by sliding them up past the front of the skewback channel as a rule inasmuch as they are usually replaced during the life of the furnace structure. At the same time, such doorframes should fit relatively close to make the furnace structure as tight as possible, yet with conventional skewback channels the outside of the web facing the doorframe has in many cases been known to bulge outwardly making it impossible to make a proper fit between the skewback channel and the doorframe. In fact, in extreme cases, such bulging might result in failure of the roof with consequent hazard and loss of production.

In the novel skewback structural shape of this invention, any such bulging or tendency to bulge is prevented. Further, this new structural shape is reversible so that as and when the furnace is rebuilt, the respective bottom and top of the new shape can be reversed, greatly lengthening the useful life thereof. Heretofore, when the lower part of the skewback channels deteriorated to a certain point under the severe conditions of their use, they have been discarded in many cases before the remainder of the furnace framework required any replacement. In addition, in the skewback structural shape of this invention, the same elements thereof that enable it to achieve marked superiority in resistance to horizontal bending thrust also enable it to be cooled. Thus, even if it be used with an archless type of doorframe, no water-cooled ledge will be required therein.

Other objects and advantages will be apparent from the following description and from the following drawings, which are illustrative only, in which,

Figure 1 is a front view of a charging door section for an open-hearth furnace employing the new skewback structural shape of this invention;

Figure 2 is a view of the assemblage shown in Figure 1 taken from inside the furnace;

Figure 3 is a view in section of a portion of the assemblage shown in Figure 1 taken along line III—III thereof;

Figure 4 is a view in elevation of the front of a skewback structural shape embodying the teachings of this invention;

Figure 5 is a view in elevation of the back of the structural shape shown in Figure 4;

Figure 6 is an end view in elevation of the structural shape shown in Figure 4;

Figure 7 is a view in section of the structural shape shown in Figure 4 taken along line VII—VII thereof; and

Figure 8 is a view in section similar to Figure 7 of a modified form of the structural shape of this invention.

Referring to the drawings, a set of buckstays 10 forming a part of the framework of an open-hearth furnace extend vertically on each side of a charging opening 11 extending through the front wall of the furnace. This opening is defined horizontally by the distance between the legs of a doorframe 12 and defined vertically by the distance between the bottom edge of the top 13 of said doorframe 12 and the top of a foreplate 14. Foreplate 14 is supported on a breast plate 15 also forming a part of the aforesaid framework between the buckstays 10. The front or outside of doorframe 12 is provided with integral door guides 16 thereon between which a charging door 17 is adapted to slide. Rods 18 pivotally connected to the lugs at the top of door 17 are also connected to elevating mechanism for operating the door to open and close the opening 11 as required. In its closed position, as shown in Figures 1 and 2, the bottom of the door 17, which as shown is of a panel type, rests upon foreplate 14. Similarly, when frame 12 is to be removed or replaced, the eyes 19 welded to the top thereof are engaged by lifting mechanism so that the doorframe can be removed. In its operative position, as shown in Figures 1 and 2, the frame may be conveniently bolted to the sides of the respective buckstays.

As shown in Figure 3, the top 13 of doorframe 12 rests in snug close fitting engagement against the smooth front side of the skewback structural shape 20 which structural shape embodies the teaching of this invention. In this way, a close relatively tight fit exists between the members 20 and the doorframe 12. The inside of the rest of the doorframe similarly fits between the buckstays 10 against the refractory walls 21 on the inside of the furnace above the hearth 22.

The skewback structural shape 20 may be provided with drilled openings 23 in the web 24 thereof against the front of which top 13 rests. Bolts 25 extend through registering openings in the clip angles 10a welded to buckstays 10 and the drilled openings 23 so that the skewback member 20 may be firmly attached to the furnace framework by the tightening of the nuts 26. Alternatively, vertical hanger rods which are not illustrated may be suspended from the upper part of the furnace framework and attached to the skewback member 20 to support the load imposed thereupon by a refractory roof 27. A skewback refractory shape 28 is interposed between the member 20 and the edge of the arching roof 27.

The front of web 24 presents, between the buckstays, a smooth planar surface against which the inside of the top 13 of doorframe 12 can rest and the doorframe itself slide during the installation and removal thereof from the furnace. On opposite side, the roof 27 transmits a generally horizontal relatively tremendous thrust against the inside or back of web 24 as shown in Figure 3 tending to bulge it in the direction of the frame 12. Such bulges which occurred with prior skewback channels might impair both the fit of the doorframe and the economy of the furnace.

In this invention, the new structural shape 20 is provided, having a section modulus about

its generally vertical neutral axis which will prevent any lateral or transverse deflection thereof in a generally horizontal direction intermediate the buckstays 10. In that way, with the structural shape of this invention, the proper fit of the doorframe 12 and the continuing economy of the furnace is assured.

In this new structural shape the flanges 29 of the embodiment as shown in Figure 7 are preferably made out of the same plate from which the web 24 is formed. Thus, each flange comprises a side 30 forming a right-angle bend with the web 24 and extending inwardly and normal thereto. A second side 31 of each flange 29 is a further right-angle bend from side 30 extending parallel to the web 24 and away from the horizontal center line thereof. A third side 32 of the flange 29 forms a further right-angle bend from side 31 but extends toward the web 24 and normal thereto. The fourth side 33 of the respective flanges 29 forms a still further right-angle bend continuation of side 32 but side 33 is in the plane of and extends toward the horizontal center line of web 24. The edge of side 33 is continuously welded to web 24 at the first right-angle bend between the said web and the side 30. Each such flange 29 thus is a box section of a hollow rectangular nature completely sealed along the length of the member 20. Moreover, the side 33 is in effect a vertical continuation of the web 24 and the weld material 34 between the edges of the sides 33 is made flush with the outside of web 24 so that the smooth planar surface thereof is unimpaired.

The flanges 29 are parallel to and equidistant from the horizontal center line of the structural shape 20 making the skewback 20 symmetrical about its horizontal center line. It is also symmetrical about its vertical center line. Each of the hollow flanges 29 is closed at its ends by the respective plates 35 welded around the edges thereof to the inside of flange 29. Preferably, the closure plates 35 are flush with the ends of the skewback 20 but they may be placed somewhat inwardly of the ends of the flanges 29. Female nipples in the form of pipe connections 36 are rigidly connected to the outside or front of the sides 33 of the flanges 29. Each pair of connections 36 adjacent the respective ends of each flange 29 communicate with the interior thereof through an opening 37 in registry with the openings in the connections 36.

As a general rule only the lower flange of a skewback member requires protection against being burned away in the course of use in a furnace structure such as an open-hearth furnace. By means of the provision of this invention, whichever of the flanges 29 is the lower can be itself directly cooled by rigging inlet and outlet water hose connections respectively (not illustrated) to the pair of pipe connections 36 communicating with the interior of whichever of the said flanges 29 is the lower. These hose connections as shown in Figures 1 and 2 are so positioned along the skewback member 20 as to lie to the respective sides of the doorframe 12. Hence, they do not interfere with the normal operation in the installation and removal of such frames. Moreover, as and when the roof of a furnace in which a structural shape 20 may be employed, is rebuilt, the top and bottom of the skewback channel can be reversed whenever the condition of the flange 29, which has been in the lower position, renders such a reversal desirable. In such a case, the lower flange 29 becomes the upper

flange and vice versa. By such means, it is evident that the skewback shape of this invention provides a member which not only has a section modulus about its generally vertical neutral axis of such a kind as to prevent lateral or transverse bulging under the horizontal thrust of roof 27, but it also provides a structural shape which is capable of a greatly extended life as a part of the framework of the particular furnace to which it is applied.

A modified embodiment of this invention is shown in cross section in Figure 8. In that figure a structural shape 44 is similar in general construction and purpose to member 20 except that in the modification, the flanges 38 are differently formed. Thus, each flange 38 involves but three right-angle bends respectively forming the sides 39, 40 and 41. The edge of side 41 is welded at 42 to the inside or back of the web 43. Various other modifications in the size and dimensions of the structural shape of this invention and of the means for fastening such to the framework of the furnace structures to which applied may be made without departing from the spirit of this invention as defined by the scope of the appended claims.

I claim:

1. An elongated reversible structural support for a skewback in an open-hearth furnace or the like, comprising, in combination, a generally vertical web adapted to bear at spaced horizontal intervals against the framework of such furnace or the like, hollow box section flanges extending along the horizontal edges of said web in symmetrical and rigid relation thereto, the section modulus of said support being sufficient to resist the thrust of the skewback without material outward bulging, and closures for the respective ends of said flanges to form cooling passages therethrough and provide coolable flanges.

2. An elongated structural support for a skewback in an open-hearth furnace or the like, comprising, in combination, a vertical web having its back engage the buckstays and framework at spaced horizontal intervals, generally tubular flanges formed integrally along the horizontal edges of said web equidistant from the horizontal center line thereof, a plate sealing off the open ends of each of said flanges in substantially flush relation with the ends of said support, said flanges having fluid circulation openings into the interior thereof intermediate their ends, whereby the bottom of said support may be placed in horizontal top position after a predetermined period of use and that flange on the bottom at the time being may be used as a cooling passage.

3. An elongated structural support member for a skewback in an open-hearth furnace or the like,

comprising, in combination, a vertical web bearing at spaced horizontal intervals against vertical framework members of said furnace or the like, box section flanges formed integrally along the horizontal top and bottom edges respectively of said support member, each of said flanges being formed from the same plate material forming said web, said flange comprising a right-angle bend inwardly of said web and normal thereto, a further right-angle bend parallel to said web extending away from the horizontal center line thereof, a further right-angle bend normal to and extending toward said web, and a remaining right-angle bend in the plane of said web extending toward its said horizontal center line, the edge of said remaining right-angle bend being welded to the first such bend, and closures for the respective ends of said flanges formed by said bends, whereby a support member is provided having a section modulus about its vertical neutral axis sufficient to withstand lateral bending while at the same time said flanges may be used as respective cooling passages.

4. An elongated skewback member subjected to intense heat in open-hearth furnaces or the like, said member having a vertical web adapted to bear at spaced horizontal intervals against vertical framework members of said furnaces or the like, box section flanges formed integrally along the horizontal top and bottom edges of said member, each of said flanges being formed from the same plate material forming said web, said flange comprising a right-angle bend inwardly of said web and normal thereto, a further right-angle bend parallel to said web extending toward the horizontal center line thereof, and a remaining right-angle bend normal to and extending to said web, the edge of said remaining right-angle bend being welded to said web, and closures for the respective ends of said flanges formed by said bends, whereby a skewback member is provided having a section modulus about its vertical neutral axis sufficient to withstand lateral bending while at the same time said flanges may be used as respective cooling passages.
